UNITED STATES PATENT OFFICE.

JAMES E. HILLS, OF BROOKLYN, NEW YORK.

DESIGN FOR A LINK CUFF-BUTTON.

SPECIFICATION forming part of Design No. 24,510, dated July 30, 1895.

Application filed June 1, 1895. Serial No. 551,414. Term of patent 14 years.

To all whom it may concern:

Be it known that I, JAMES E. HILLS, residing at the city of Brooklyn, county of Kings, State of New York, have invented a Design for Link Cuff-Buttons, of which the following is a specification.

Reference is to be had to the accompanying drawings, illustrating my design, in which—

Figure 1 is a plan view of a link cuff-button embodying my design, and Fig. 2 is a front elevation thereof.

My novel design for a link cuff-button consists of the horizontally-disposed rearwardly-curved shank portion 1 as viewed in connection with the angularly-placed heads 2, 3,

said heads leaning toward each other from the rear toward the front of the button and connected to opposite ends of the shank, the head 2 at about the center of its back and the head 3 at a point where its inner edge is ²⁰ nearest to the inner edge of head 2.

What I claim is—

The design for a link cuff-button substantially as herein shown and described.

In testimony whereof I affix my signature ²⁵ in the presence of two witnesses.

JAMES E. HILLS.

Witnesses:

R. P. HESS,

P. N. TURNER.
